GEORG SENFTNER, OF BERLIN, GERMANY, ASSIGNOR TO THE FIRM DR. SENFTNER & CO. G. M. B. H., OF STETTIN, GERMANY

RADIOACTIVE MEANS FOR ACTIVATING WATER IN BOTTLES

Application filed March 11, 1927, Serial No. 174,540, and in Germany March 25, 1926.

The present invention relates to a radioactive means for activating water, especially table waters, in bottles. On account of the expensiveness of the radio-active preparations it is of the greatest importance, when they are intended to be used for the activation of mineral waters to make provisions for preventing the loss of the radio-active preparations which are capable to preserve their full activity for a very long time. When the radio-activation of the water has to be carried out in the bottles, or in other words when the radio-active substance has to be inserted into the bottle—this being advisable especially for the reason that thereby the high radio-activity of the water at the moment when it has to be used is best ensured—there exists the danger, that the radio-active substance drops out of the bottle when the water is being poured out. This danger exists also when the radio-active substance is enclosed in a small envelope or capsule of porous material or of a material which is permeable to the emanation. If, on the other hand, the envelope is made of such a size that it cannot readily drop out of the bottle, it might get across the bottle neck at the pouring out of the liquid and clog the bottle neck.

Radio-active substance fixed on the bottom, on the inner surface of the bottle or other vessel cannot be totally surrounded by the water so that the substance is not completely utilized. Moreover the fixed connection of the radio-active substance with the vessel requires a complicated and therefore expensive construction. When the vessel is broken, the radio-active substance will be destroyed generally. It is further difficult and sometimes impossible to remove the radio-active mass from the vessel for repair or renewal or when the vessel has to be cleaned.

All these inconveniences are avoided by the present invention. According to the invention the insoluble radio-active mass is enclosed by a resilient or elastic spreadable body, which allows the insertion into and the intentional removing from the bottle, but prevents accidental dropping out when the water or the like is being poured out, clogging of the bottle neck, or resting of the radio-active

mass directly on the bottom or on the wall of the bottle. This resilient or elastic body may be constructed in different manners. It may, for instance, consist of an envelope or sleeve of small size enclosing the radio-active mass and having resilient arms extending in different directions. Or it is formed by elastic trellis work which encloses the radio-active mass and is of such size that it can be inserted or removed through the bottle neck only when the elastic trellis work has been compressed. In this case the elastic spreadable body has the shape of a small elastic cage in which the radio-active mass is arranged directly or indirectly.

Two embodiments of the invention are illustrated, by way of example, in the accompanying drawings in which:—

Fig. 1 shows a side elevation of one form of construction.

Fig. 2 is a longitudinal section of the construction shown in Fig. 1.

Fig. 3 shows a top plan view of the same construction.

Fig. 4 is a top plan view of a casing of the second form of construction.

Referring to Figs. 1 and 3 the radio-active mass *a* is enclosed in an envelope *b* of wire gauze which is loosely mounted in a wire cage *c*. The cage *c* is formed by rods *d* which, as shown in Figs. 1 and 2, are bent outwards at the middle portion and joined at the ends. The upper and lower ends of the rods or wires *d* are fixed to plates *e* by soldering or in any other convenient manner. By the curving of the cage *c* at the middle a certain elasticity is obtained so that the cage can be forced through a bottle neck the inner diameter of which is slightly smaller than the greatest diameter of the cage at the middle of the wires *d*. This greatest diameter at the middle of the cage must therefore be selected accordingly in order to fulfill the object. When the cage has been inserted into the bottle it cannot drop out when the water is being poured out or when the bottle is turned upside down. As the water can freely flow through the cage it is impossible that the bottle neck be clogged, even when the cage

should get into the lower end of the bottle neck.

To remove the cage from the bottle a convenient tool, for instance a wire hook, has to be inserted to grip the cage which is slightly compressed when passing through the bottle neck. The cage containing the radio-active mass can then be used in another bottle, or the bottle may be cleansed if desired. The cage at the same time prevents the radioactive substance from resting directly upon the bottom or wall of the bottle or other vessel, this being essential for the thorough utilization of the radio-active substance.

In the form of construction shown in Fig. 4, P is the radio-active mass, enclosed in an envelope of insoluble material which however allows the emanation to pass, or a radioactive mass combined with an insoluble mass which allows the emanation to pass. F are resilient arms, the outer ends r of which are bent at an angle, said arms F being arranged on or connected with part P. The arms F, and their bent ends r (whose shape may be selected at will) extend in different directions so that the preparation or envelope P cannot come into direct contact with a plane or bent surface.

Numerous changes of construction may be made without departing from the spirit and scope of the invention. The wires or rods of the small cage (Figs. 1 to 3) may be directly united by soldering instead of being fixed to the plates, or they might be united by small caps which may be fixed by soldering or the like. The wires or rods may also be arranged in such a manner that they are narrowly joined only at one end of the cage whereas the bulged out part is arranged at the other end of the rods or wires where they may be united by a larger plate or the like. In this case the point, which opposes resistance against accidental dropping out of the cage from the bottle, will then be the corresponding end of the cage and not the middle, this end being elastic to permit corresponding compression for removal of the cage from the bottle. The cage for the radio-active substance might further be made from elastic plaited work or the like, or the wires of the cage, instead of being parallel to the axial direction, might be perpendicular the axial direction, or a wire spiral might be used to form the cage.

The spreadable body or cage may be of any material provided it be of such a kind that it will not be corroded by the liquid contained in the bottle, or that this liquid will not be unfavorably influenced by said material. Suitable metals or metal alloys are preferably used, as nickel or nickel-plated rods, aluminium, gilded wires or rods, and the like.

Having now particularly described and

ascertained the nature of my said invention, I declare that what I claim is:

Means for subjecting water in a bottle to the action of a medicinal agent comprising a mass of said agent located in an open metallic elastic cage which encircles said mass, said cage comprising a plurality of resilient members which are outwardly flared so that the width of said cage is greater in the middle thereof than at the ends thereof, said resilient members being sufficiently yieldable to enable them to be compressed to permit said cage to pass through the neck of a bottle, said cage being retained within the body of said bottle by the resilient action of said members.

In testimony whereof I have hereunto set my hand.

DR. GEORG SENFTNER.
